METHOD AND APPARATUS FOR SEPARATING MATERIAL INTO CONSTITUENTS OF DIFFERENT SPECIFIC GRAVITY

Gustave Andre Vissac, Calgary, Alberta, Canada

Application March 16, 1936, Serial No. 69,187

8 Claims. (Cl. 209—455)

This invention relates to a method of separating material into constituents of different specific gravities and to an apparatus, i. e. a jig, for carrying out such method.

5 Different methods and apparatus for effecting the separation of material into constituents of different specific gravities by means of pulsating currents of water, have been suggested and used, and my invention, which has been developed more 10 particularly in connection with the separation of coal from its impurities, is an improvement on such methods and apparatus.

The jig, according to the invention, includes a screen across which material to be separated is 15 adapted to pass, the screen being supported in a hutch filled with water and associated with an air pressure and vacuum tank which are adapted to be periodically brought into communication with it by means of rotating valves, the pressure 20 tank being provided also with a bye-pass through which a substantially continuous current of water may, when desired, be allowed to flow into the hutch.

One of the great difficulties in prior methods and 25 apparatus using pulsating currents of water has been the large volume of water necessary to obtain sufficiently active surges and a reasonable output. According to the present invention this difficulty is entirely overcome by particularly 30 shaping the hutch and tanks and using certain guiding plates therein and employing extremely sensitive variable speed drives for the rotating valves so that in each case a speed may be obtained at which the pressure tank and hutch act 35 as resonators, with the result that the pulsations of the air and water are greatly amplified by the effect of resonance. In this way the most efficient surges with the minimum amount of power are obtained.

40 Another great difficulty in prior methods and apparatus has been to produce the form of surge exactly adapted to each particular problem of separation. Depending on the sizes and specific gravities of the particles to be separated, the most 45 efficient surge may have a slow or a sharp rise, a short or a long top and a sharp or a slow fall, which latter may even acquire a negative value in the form of a suction. Thus, an undesirable shape of surge is a straight line in the rise or fall, 50 as it means a constant speed period of motion during which the sizes that can be separated are limited by the law of equivalence. A desirable shape of surge is a parabolic curve, which means accelerated motions and separation by specific 55 gravities alone independently of sizes. Again

with a surge having too sharp a rise small particles of refuse can be washed over before they can be drawn down on the fall of the surge; while with a surge having too sharp and brief a fall or a suction at the end of the fall, small particles 5 of refuse may be drawn down through the screen into the bottom of the hutch. The apparatus of the present invention, however, provides the necessary means and enables the necessary adjustments of such means to permit the production 10 of surges of the desired form for any given case.

When the proper and correct stratification of the products to be separated has been achieved, another great difficulty in prior methods and apparatus has been to withdraw the separated constituents 15 correctly and consistently. The constancy of the degree of separation is generally achieved by regulating the removal of one of the constituents, the refuse in the case of coals, through a refuse extractor or evacuator, the remaining or clean constituent being washed over 20 the weir of the jig.

According to my invention, the regulation of the removal of the refuse is achieved by combining a float control dependent on the specific gravity 25 of part of the bed of material to be separated, with a float control dependent on the resistance of this part of the bed caused by the accumulation of material.

The shape and efficiency of the surges caused 30 in the hutch by its periodic communication with the pressure or vacuum tanks are controlled by (1) driving the rotating valves at exactly the speed capable of giving the effects of resonance, this speed being determined by observation in 35 each case; (2) the setting of the valve controlling the bye-pass from the pressure tank to the hutch; (3) the regulation of the resistance or of the assistance presented to the surges in the hutch by a plate freely hung in the path of movement of 40 the water passing between either of the tanks and the screen, this regulation being effected by adjusting the angular relation to the plate of an arm connected with it and by adjusting the position of a weight on this arm; (4) the relative 45 angular settings of the rotating valves from the pressure and vacuum tanks; (5) the opening of the valves on feed or drain pipes from the pressure and vacuum tanks.

The means for maintaining constant the degree 50 of separation of the material comprise a float in the bed of material which is formed on the screen, this float controlling the operation of a switch in the circuit of a motor driving an evacuator for ejecting the heavier constituent of the 55

material. The evacuator is situated at the lower end of the screen in a chamber separate from the hutch and the arrangement is such that the operation of the evacuator is regulated by the specific gravity of the heavier constituent. This control is supplemented by a further control of the amount of a flushing current of water for the heavier constituent, this control being effected by valves connected to a float whose movement is responsive to the resistance offered by the material on the screen to the upward passage of water therethrough and thus to the accumulation of material on the bed.

In the accompanying drawing:

Figure 1 is a somewhat diagrammatic cross-section of the apparatus.

Figure 2 is a face view of a cam used in connection therewith, and

Figure 3 is a cross-section on the line 3—3 of Figure 2.

The main body of the apparatus is composed of a round bottomed shell 1 divided by a wall 2 into a hutch 3 and pressure tank 4 and having alongside the pressure tank a vacuum tank 5. From the pressure tank 4 runs a pipe 6 having therein a valve 7 and connected either to the pressure side of a pump or to a certain constant head of water. From the vacuum tank likewise leads a pipe 8 having therein a valve 9 and connected to the suction side of a pump or to a draft tube. The openings from the hutch to pressure and vacuum tanks 4 and 5 are adapted to be closed by butterfly valves 10 and 11 respectively, which may be rotated by belts or chains 13 and 14 from variable speed drives operated from a suitable source of power such as a motor 12. When the valve 11 is closed, a partial vacuum is formed in the tank 5 owing to the fact that water is constantly flowing therefrom through the pipe 8. When the valve is opened, water is drawn into the tank 5 from the hutch. The valves 10 and 11 may be adjusted on their shafts to change their angular setting with respect to one another so that, instead of one being closed during the whole time the other is open, as shown in the drawings, one may open somewhat before the other closes. If, for example, the valve 11 opened somewhat before the valve 10 closed, the top of the surge would be flattened and the fall of the surge would be sharpened. If, on the other hand, the valve 10 opened before the valve 11 closed, the rise of the surge would be smoothed.

In some cases, in order to produce a particular shape of surge in the hutch, it may be desirable to drive the valve controlling the opening from the pressure tank 4 through an elliptical sprocket 15. In addition to the main opening from the pressure tank 4 to the hutch 3, there is a by-pass opening 16 controlled by an adjustable valve 17. The pressure tank 4 is provided in its interior with suitable plates 18 to reduce eddies, and regularise pressures on the whole surface of the screen 22.

Freely swung from the bottom of the wall 2 is a plate 19 extending entirely across the apparatus for aiding in the control of the shape of the surges in the hutch. To the rotatable shaft supporting this plate is adjustably fixed an arm 20 and on the arm a weight 21 is adjustable. The amount of resistance which the plate will present to a surge in the hutch and the point in the rise or fall of the surge at which such resistance will occur may thus be controlled by adjusting the angular setting of the arm 20 and the setting of the weight 21 on the latter. Across the hutch 3

is fixed a screen 22, below which a plate 23 articulated on wall 2 gives the proper lateral component to the surge, to aid feeding of material across the screen. The delivery opening of a suitable hopper or chute for the material to be separated is situated above the screen at the side nearest the pressure tank 4.

Connected with the hutch through an opening 24 in the left hand wall 25 thereof is a pressure chamber 26 which is connected at the bottom 10 with a sealed elevator 27 for the heavier constituent of the material which passes out of the hutch through the opening 24. In the chamber 26 in front of the opening 24 is a star evacuator 28 for this constituent, which is driven through a suitable drive 29 from a variable speed motor 30. An adjustable sludge valve 62, connected to the elevator 27 or to a sludge tank, is positioned in the bottom of the hutch, for the extraction of small particles of the heavier constituent drawn down through the screen 22 by suction.

Leading from the chamber 26 is a pipe 31 through which water may flow out from the chamber, the opening of this pipe being controlled by valves 32a and 32b connected to a stem 33 having mounted thereon a float 34. It is to be noted that the valves 32a and 32b are thoroughly compensated so that a minimum of force to move them is required. The former is subjected to a downward and the latter to an upward pressure, and the latter is slightly smaller than the former to take care of the difference in hydrostatic pressure owing to the different vertical elevations.

Just above the screen 22 and near the opening 24 is a float 35 mounted on a rod 36 connected to an arm 37 of a bell crank lever pivoted at 38 and the other arm 39 of which is pivotally connected at 40 to a rod 41 suitably supported by 40 rollers. At the right hand end of this rod are adjustable stops 42 and 43, one of which upon sufficient movement of the rod in a horizontal direction is adapted to engage a circular projection 44 of a cylinder 45 to which is fixed a cam 46. The cylinder 45 is slidable along but rotates with a shaft 47 suitably driven, as for example through a drive 48, from the motor 12. The left hand face of the cam is formed with an indented track as shown in Figures 2 and 3 while at the right hand side its circumference is continuous.

Mounted on a rod 49 moving in a guide 50 is a roller 51 and pivotally connected to the rod 49 is a rocker arm 52 centrally pivoted at 53 and pivoted as at 54 at its other end to a rod 55 moving in guides 56 and continually urged upwards by a spring 57. The rocker arm 52 has mounted on it a mercuroid tube switch 52a controlling the circuit 52b feeding the motor 30.

The operation of the device is as follows:

The material to be separated is allowed to feed from the hopper or chute to the screen 22. The opening of the valves 7 and 9 and the by-pass valve 17, the speed of rotation of the butterfly valves 10 and 11, their angular setting with respect to one another and consequently the relation of their times of opening and closing, the angular setting of the elliptical sprocket 15 with respect to the valve 10, the angular setting of the arm 20 with respect to the plate 19 and the position of the weight 21 on the arm 20 are all adjusted to give in the hutch 3 surges of the required form and frequency which, as will be understood, vary according to the material being treated and the degree of separation required. Owing to the 75

water surges in the hutch, the float 35 will oscillate about a position of rest which is a function of the apparent specific gravity of the medium in which it is. When the medium is water alone, the position of rest will be such as to bring the bottom of the float very close to, if not resting on, the screen 22. In this position of the float the rod 41 will be sufficiently far to the right of the position in which it is shown in the drawing not only to bring the stop 43 into contact with the circular projection 44 but to hold the cylinder and the cam 46 so far to the right on the shaft 47 that the roller 51 will be resting on the cylinder 45 and the rocker arm 52 will consequently have the opposite angularity to that shown, the mercury in the tube 52a being thus at the left hand end of the latter so that the circuit 52b for the motor 30 is broken and the evacuator 28 will not be rotating.

In these circumstances a bed of material will be formed on the screen 22, the portion of which nearest the wall 25 will be stratified. As the specific gravity of the bed increases, the float 35, which is normally entirely submerged in the bed, will rise and when the predetermined thickness and consequent specific gravity of the bed has been reached, the rise of the float will be such as to draw the arm 41 and consequently the cam 46 sufficiently to the left to cause the roller 51 to enter the indented cam track 58 of the cam. Owing to the anti-clockwise rotation of this cam, as shown by the arrow in Figure 2, the roller 51 will, through its contact with the wall 59 of the track 58, be forced up onto the outer circumference of the cam. As soon as the roller does reach the outer circumference of the cam, the latter will be free to move under the pull of the stop 42 on the rod 41 slightly further to the right so that the roller will ride on its continuous circumference. The rise of the roller 51 will force the rod 49 upward and the rod 55 downward against the action of the spring 57 so that the mercuroid tube switch 52a will be brought into the position shown in Figure 1 of the drawing and the circuit feeding the motor will be established. As soon as this happens the evacuator 24 will begin rotation to evacuate refuse into the chamber 26. Even when the roller 51 is not riding on the continuous circumference of the cam 46, the lip 60 on the latter will prevent the roller from having any greater drop than that to the point 61, which is insufficient to open the switch 52a.

The speed of the motor 30 has been previously so adjusted as to drive the evacuator at the best average speed to keep the thickness of the bed constant. So long as the thickness and consequently the apparent specific gravity of the bed remains constant the average position of the float 35 will remain the same, i. e. it will oscillate about a position of rest such that neither the stop 42 nor the stop 43 will touch the projection 44, the stops being set apart a distance corresponding to the maximum amplitude of oscillation of the float.

If, for any reason, the thickness of the bed alters, the controls actuated by the floats 34 and 35 will operate to bring it back to normal. If the bed gets thinner, there will be a decrease in its specific gravity as a result of which the float 35 will drop, pushing the rod 41 to the right and, through consequent contact of the stop 43 with the projection 44, moving the cam 46 to the right so that the roller 51 will, under the action of the spring 57, drop off it onto the cylinder 45. As the circuit feeding the motor 30 will thus be

broken the evacuator 28 will stop and the bed will be able to build up to its normal thickness.

In the above case, the action of the control described will be supplemented by the action of the controls operated by the float 34. The pressure in chamber 26 is directly proportional to the resistance of the bed on the screen 22 to the upward passage of water through it, and the position of the float 34 and of the valves 32a and 32b attached to its stem 33 depends entirely upon the pressure prevailing in the chamber 26. Therefore, the amount by which the valves 32a and 32b are opened and, consequently, the amount of the current through the opening 24 and out through the pipe 31 tending to carry refuse with it will be proportional to the resistance of the bed. When the bed gets thinner this resistance will decrease, the float 34 will assume a lower position and the flushing current will be decreased or even shut off entirely. If the thickness of the bed increases above normal, the float 34 will rise, thus opening the valves 32a and 32b wider and causing an increase in the flushing current. Even though the refuse evacuator 28 is turning at a constant speed, this increase in the flushing current causes a quicker and better filling of the troughs of the star evacuator, with the result that the thickness of the bed will be reduced to normal.

The two controls supplement and complete each other and regulate most efficiently the separation of the material in all cases. As is well known, a density float such as 35 is safer and more sensitive with pieces of small size, while a pressure float such as 34 is safer and more sensitive with pieces of large size. The action of float 34 operating compensated, direct acting valves is quick and sensitive and the action of float 35 is also most sensitive, since roller bearings can be used at all points of rotation and a very small displacement of the average oscillating position of the float and, consequently, a very small displacement of cam 46 is sufficient to catch the roller 51 or to let it drop. The power required from the float 35 is thus only that necessary for this small displacement, as the rotation of the cam is effected from an auxiliary source of power.

This application is a continuation in part of my co-pending application Serial No. 716,707, filed March 21, 1934.

I claim:

1. A jig comprising a hutch, a screen over the hutch, a pressure tank, means for continuously forcing water into said tank, a vacuum tank, means for continuously withdrawing water from said vacuum tank, an opening below said screen from said hutch to each of said tanks, means for periodically and substantially alternately closing said openings to cause surges of water in said hutch, and a swingable plate freely hung in the hutch in the path of movement of any water passing back and forth between the screen and the openings from the hutch to the pressure and vacuum tanks and on an axis of pivotal movement transverse to the path of the water, said plate being adapted evenly to distribute the flow of water over the screen during one surge thereof and to swing back to permit the free movement of water during the return surge thereof.

2. A jig according to claim 1 comprising means for variably adjusting the inertia of the swingable plate to modify the form of the surges.

3. A jig comprising a hutch, a screen over the hutch, a pressure tank, means for continuously forcing water into said tank, a vacuum tank,

- means for continuously withdrawing water from said vacuum tank, an opening below said screen from said hutch to each of said tanks, means for periodically and substantially alternately closing 5 said openings to cause surges of water in said hutch, and a plate pivoted on the wall of the hutch below the screen on an axis of pivotal movement transverse to the path of the water and in the path of the upward surges of water 10 to give a lateral component to said surges.
4. A jig comprising a round bottomed shell, a pressure tank with a closed top and an open topped hutch formed in said shell side by side, a downwardly directed opening from the tank to 15 the hutch substantially above the bottom of the shell, a valve in said opening, plates extending outwardly and downwardly from two opposite walls of the tank, a connection to a source of water under pressure in one of said walls below 20 the point of juncture of the plate with the wall, said plate thus directing incoming water downwardly in the tank, and together with the other plate tending to reduce eddies in the tank, a screen across the hutch, and means for rotating 25 said valve.
5. A jig comprising a hutch, a screen over the hutch, means for causing surges of water through the screen, means for passing material to be separated across the screen, a refuse evacuator 30 associated with said screen, a motor driving the evacuator, a switch for the motor, a switch operating member, a float in the material above the screen and responsive to the specific gravity of said material, a rod connected to the float having stops thereon, a constantly revolving cam 35 adapted to be moved axially by one of the stops upon any change in the average position of the float, and being adapted upon such movement to engage or disengage the switch operating member 40 to control the motor of the evacuator.

6. A jig comprising a hutch, a screen over the hutch means for causing surges of water through the screen, means for passing material to be separated across the screen, a water pressure chamber connected with the hutch, means in the pressure chamber for removing material from the screen, a water discharge opening in the pressure chamber, a valve normally closing the water discharge opening, a float connected to the valve responsive to an increase in the water pressure in the pressure chamber to permit water to flow therefrom, 10 said flow of water from the pressure chamber being adapted to create a flow of water substantially across the screen to assist in the removal of the material.

7. A jig, as defined in claim 6, in which the discharge valve comprises a pair of valves mounted one above the other on a stem connected to the float, the lower valve being smaller than the upper one to compensate for the difference in 20 hydrostatic pressure owing to their different vertical positions.

8. A jig comprising a hutch, a screen over the hutch, means for causing surges of water through said screen, means for passing material to be separated across said screen, a separate discharge chamber communicating with the hutch through an opening at the discharge end 25 of the screen, a rotary evacuating valve in said opening for removing material from the screen, means including a float for actuating the rotary valve, a flushing valve in said separate chamber controlling the only outlet thereof, and means including a float for actuating the flushing valve 30 for selectively creating a flow of water substantially across the screen to assist in the evacuation of the material.

GUSTAVE ANDRE VISSAC. 40
